HATCH CONSTRUCTION

Charles David Bonsall, Pittsburgh, Pa., assignor
to P. H. Murphy Company, New Kensington,
Pa., a corporation of Pennsylvania

Application July 25, 1935, Serial No. 33,041
Renewed May 11, 1936

12 Claims. (Cl. 108—5)

This invention relates to the hatchway construction of a car roof. It has for its principal objects to produce a strong and durable weather-proof hatchway construction of simple and economical construction. The invention consists in the hatchway construction and in the combinations and arrangements of parts hereinafter described and claimed.

In the accompanying drawings, which form part of this specification and wherein like symbols refer to like parts wherever they occur,

Fig. 1 is a plan view of the end portion of a metal car roof provided on each side of the ridge with a hatchway construction embodying my invention,

Fig. 2 is a vertical section through one of the hatchways, the section being taken transversely of the roof on the line 2—2 of Fig. 1,

Fig. 3 is a vertical section through said hatchway, the section being taken longitudinally of the roof on the line 3—3 of Fig. 1,

Fig. 4 is a fragmentary plan view of the roof in the region of said hatchway, with parts shown broken away,

Fig. 5 is a vertical section through the hatch sheet of the roof on the line 3—3 in Fig. 1,

Fig. 6 is a plan view of the metal hatch frame or hopper member of said hatchway; and

Fig. 7 is a view of said frame partly in side elevation and partly in vertical cross-section.

Referring to the accompanying drawings, my invention is shown in connection with a refrigerator car equipped with a metal car roof comprising self-supporting sheets 1 of rolled steel that span from side plate 2 to side plate 2 of the car and have their ends rigidly secured to the sloping top flanges of eaves angle strips 3 whose vertical flanges are secured to the outer faces of said side plates and cover the upper end of side sheathing 4. The roof sheets are provided along their adjacent margins with upstanding flanges 5 that are straddled by seam caps 5a that are riveted to said flanges and to the eaves angle strips 3. The roof sheets have depending eaves flanges 6 that overhang the upper end of side fascia boards 7 that are secured to the side sheathing with their tops substantially flush with the tops of the respective side plates. At the end of the car the end roof sheet is secured to the outstanding upper flange of an end angle strip 8 whose vertical flange is bolted to the outer face of the end plate 9 of the car and covers the upper end of the end sheathing 10. The end fascia board 11 is secured to the outer face of the end sheathing; and the outer margin of said end sheet has a depending flange 12 that overhangs said end fascia board. The car is provided with suitable insulation 13; and a suitable insulating lining 14 is suspended from the carlines 15 of the car.

One of the roof sheets, hereinafter referred to

as a hatch sheet, has one or two hatchway openings which lead into the ice bunker of the car. The hatchway opening is a square-cornered opening 16 located in the top of an upstanding boss 17 that is pressed in the hatch sheet. In 5 the construction illustrated, the hatchway opening is defined by a wooden hatch frame 18 supported between and extending above adjacent carlines 15 and provided above said carlines and the general plane of the roof with a round-cornered wooden edge frame 19 whose outer sides slope downwardly and outwardly. The raised boss 17 in the hatch sheet is shaped to snugly fit the edge frame 19 of the wooden hatch frame 18; that is, said boss is provided with rounded 15 corners and its side wall slopes downwardly and outwardly to conform to the shape of said edge frame.

The wooden hatch frame is provided with a sheet metal flashing or liner 20 whose upper end 20 is flanged outwardly, as at 21, between the upper edge of said frame and the underside of the boss 17 in the hatch sheet. The lower end of said liner is preferably flanged outwardly, as at 22, beneath the insulating lining 14. Located in 25 the upper end of the liner or flashing 20 is a strong and rigid hopper member or hatchway frame 23 of metal that is provided at its top with a flange 24 that extends outwardly over the top of the hatch sheet boss 17 and thence downwardly over the sloping side walls thereof. The metal hatch frame 23 snugly fits the metal hatch liner 20 and the boss 17 of the hatch sheet and has its sides converging downwardly to constitute a seat for a closure in the form of a tapered 30 wooden plug 25 of the type commonly used for closing the hatchway openings. The upper portions of the wooden hatch frame 18 and the metal liner 20 therefor are also beveled to conform to the downwardly converging walls of the metal 35 hatch frame 23. The wooden plug is carried by a metal cover 26 which is preferably secured by a hinge 27 to an adjacent seam cap 5a. The margins 28 of the metal cover slope downwardly and outwardly to conform to the slope of the 40 metal hatch frame 23. The wooden plug is carried by a metal cover 26 which is preferably secured by a hinge 27 to an adjacent seam cap 5a. The margins 28 of the metal cover slope downwardly and outwardly to conform to the slope of the 45 metal hatch frame 23. The wooden plug is carried by a metal cover 26 which is preferably secured by a hinge 27 to an adjacent seam cap 5a. The margins 28 of the metal cover slope downwardly and outwardly to conform to the slope of the 50 metal hatch frame 23. The wooden plug is carried by a metal cover 26 which is preferably secured by a hinge 27 to an adjacent seam cap 5a. The margins 28 of the metal cover slope downwardly and outwardly to conform to the slope of the 55 metal hatch frame 23. The wooden plug is carried by a metal cover 26 which is preferably secured by a hinge 27 to an adjacent seam cap 5a. The margins 28 of the metal cover slope downwardly and outwardly to conform to the slope of the 60 metal hatch frame 23.

The hereinbefore described hatch construction has several advantages. The boss in the hatch sheet snugly fits the beveled and round-cornered 50 wooden hatch frame and the hatch opening is located in the top of said sheet above the drainage level thereof. The metal hatch lining serves as a weatherproofing flashing for the opening in the wooden hatch frame. The metal hatch frame 55 provides a square-cornered seat for the square-cornered hatch plug; it also serves to reinforce the hatch sheet boss and the wooden hatch frame and to hold the hatch sheet down on the car; and it also affords a suitable support for the ice in 60

course of loading and protects the upper portions of the hatch lining and the hatch sheet boss from being damaged.

What I claim is:

5. 1. A hatch construction for car roofs comprising a wooden hatch frame having a portion extending above the body portion of said roof, a roof sheet having an integral portion thereof pressed upwardly to form a hollow upstanding boss there-
10 in that covers said portion of said hatch frame and has a hatch opening cut in its top, and a metal hatch frame mounted in said wooden hatch frame.
15 2. A hatch construction for car roofs comprising a wooden hatch frame having a portion extending above the body portion of said roof and provided with a downwardly and outwardly inclined exterior side surface, a roof sheet having an integral portion thereof pressed upwardly to
20 form a hollow upstanding boss therein that fits around said portion of said hatch frame and has a hatch opening cut in its top, and a metal hatch frame mounted in said wooden hatch frame, said boss having a sloping side wall conforming to the
25 inclined exterior side surface of said portion of said hatch frame.
30 3. A hatch construction for car roofs comprising a wooden hatch frame having a portion extending above the body portion of said roof and provided with a downwardly and outwardly inclined exterior side surface, a roof sheet having an integral portion thereof pressed upwardly to form a hollow upstanding boss therein that fits around said portion of said hatch frame and has
35 a hatch opening cut in its top, and a metal hatch frame mounted in said wooden hatch frame, said boss having a sloping side wall conforming to the inclined exterior side surface of said portion of said hatch frame, said metal hatch frame being
40 provided with an outstanding flange that overlaps the top of said boss and terminates in a downwardly and outwardly inclined portion that bears against the sloping side wall of said boss.
45 4. A hatch construction for car roofs comprising a wooden hatch frame having a portion extending above the body portion of said roof and provided with a downwardly and outwardly inclined exterior side surface, a hatch sheet having a hollow upstanding boss therein that fits said
50 portion of said hatch frame and has a hatch opening in its top, said boss having a sloping side wall conforming to the inclined exterior side surface of said portion of said hatch sheet, a metal lining for said wooden hatchway, and a metal hatch
55 frame having a portion inside said lining, and a flange that extends outwardly over the top of said boss and terminates in an inclined portion that bears against and conforms to the sloping side wall thereof.
60 5. A hatch construction for car roofs comprising a wooden hatch frame having a portion extending above the body portion of said roof and provided with a downwardly and outwardly inclined exterior side surface, a hatch sheet having a hollow upstanding boss therein that fits said portion of said hatch frame and has a hatch opening in its top, said boss having a sloping side wall conforming to the inclined exterior side surface of said portion of said hatch sheet, a metal lining
65 for said wooden hatchway, said lining being provided at its top with a flange that overlaps the upper edge of said wooden hatch frame and ex-

tends beneath the top of said boss, and a metal hatch frame mounted in said wooden hatch frame, said metal hatch frame being provided with an outstanding flange that overlaps the top of said boss and terminates in an inclined portion that bears against and conforms to the sloping side wall of said boss. 5

6. A hatch construction for car roofs comprising a wooden hatch frame having a portion extending above the body portion of said roof and provided with a downwardly and outwardly inclined exterior side surface, a hatch sheet having an upstanding boss pressed therein that fits around said portion of said hatchway and has a hatch opening in its top, said boss having a sloping side wall conforming to the inclined exterior side surface of said portion of said hatch sheet, a metal lining for said wooden hatchway, said lining being provided at its top with a flange that overlaps the upper edge of said wooden hatch frame and extends beneath the top of said boss, a metal hatch frame mounted in said wooden hatch frame, said metal hatch frame being provided with an outstanding flange that overlaps the top of said boss and terminates in an inclined portion that bears against and conforms to the sloping side wall of said boss, and a cover resting on the top of said metal hatch frame and having sloping marginal portions resting on and conforming to the sloping side walls of said boss. 15 20 25

7. A roof sheet for a car roof, said roof sheet being made of rolled metal having an upstanding boss pressed therein integral therewith, said boss having a portion cut from the top thereof forming a hatch opening therein. 30

8. A roof sheet for a car roof, said roof sheet having an upstanding boss pressed therein integral therewith, said boss being provided with downwardly and outwardly sloping side walls and having a square-cornered hatch opening cut in the top thereof. 40

9. A hatch construction for a car roof comprising a roof sheet made of rolled metal having an upstanding integral boss pressed therein that has a portion cut from its top forming a hatch opening therein, and a metal hatch frame in said boss extending downwardly from the hatch opening in the top thereof. 45

10. A roofing sheet for car roofs comprising a rolled metal section of sufficient size to constitute a complete section of a sectional, metal car roof, said section being formed with an upstanding integral boss pressed therein, said boss having a portion cut out from the top thereof forming a hatch opening therein. 50 55

11. A roofing sheet for car roofs comprising a rolled metal section of sufficient size to constitute a complete section of a sectional, metal car roof, said section being formed with an upstanding integral boss pressed therein, said boss being provided with downwardly and outwardly sloping side walls and having a square cornered hatch opening in the top thereof. 60

12. A roofing sheet for car roofs comprising a rolled metal section of sufficient size to constitute a complete section of a sectional, metal car roof, said section having an upstanding boss pressed therein that has a portion cut from its top forming a hatch opening therein, and a metal hatch frame in said boss extending downwardly from the hatch opening in the top thereof. 65 70
